(57) **CLAIM**

I claim the ornamental design for the mounting bracket for marine equipment, as shown and described.

DESCRIPTION

FIG. 1 is a perspective view of the mounting bracket for marine equipment;

FIG. 2 is a front view thereof;

FIG. 3 is a back view thereof;

FIG. 4 is a top view thereof;

FIG. 5 is a bottom view thereof;

FIG. 6 is a side view thereof;

FIG. 7 is a side view thereof showing the side opposite that shown in FIG. 6.

The broken lines shown in the drawings are for the purpose of illustrating portions of the article that form no part of the claimed design.
